UNITED STATES PATENT OFFICE

JOSEPH LOTTO, OF ASTORIA, NEW YORK

DESIGN FOR A TOY CABINET

Application filed July 19, 1932. Serial No. 44,377. Term of patent 7 years.

To all whom it may concern:

Be it known that I, JOSEPH LOTTO, a citizen of Switzerland, residing at Astoria, in the county of Queens and State of New York, have invented a new, original, and ornamental Design for a Toy Cabinet, of which the following is a specification, reference being had to the accompanying drawing, forming a part thereof. The figure is a perspective view of a toy cabinet, showing my design.

I claim:

The ornamental design for a toy cabinet, as shown.

JOSEPH LOTTO.
